WARP CREEL

Ralph H. Balch and Thomas C. Campbell, Cumberland, Md., assignors to Celanese Corporation of America, a corporation of Delaware

Original application January 6, 1936, Serial No. 57,746. Divided and this application January 26, 1937, Serial No. 122,334

4 Claims. (Cl. 242—131)

This invention relates to a device for forming warps from threads and especially for forming warps from threads wound on bobbins or spools.

This application is a division of my application S. No. 57,746 filed January 6, 1936.

An object of the invention is the provision of a device for the economic production of warps wherein a uniform tension exists on each warp end. Another object of the invention is the provision of a device for the production of warps from continuous filament threads wherein there is less breaking of the filaments than by methods heretofore employed. Other objects of the invention will appear from the following detailed description.

Fig. 1 is a side view of a creel constructed in accordance with our invention.

Fig. 2 is a front view of a part of the device shown in Fig. 1.

Fig. 3 is a front view in detail of the roller guides that form the heads of the device.

In forming warps, especially when the thread is supplied wound on spools, it has been customary to build the warp sheet in sections on a warp mill, which sheet was built in a varying number of sections from two up. The present invention, which provides as a source of threads, two or three times more spools than heretofore possible, in the same amount of floor space and a uniform individual tension on each thread permits the forming of warp sheets in but two to four sections which formerly were made in 4 to 12 sections.

To overcome the objections to forming warps in a multiplicity of sections, there has been developed cone creels. These, however, besides requiring a large amount of floor space and a large investment, also necessitate the additional costly processing step of first coning the yarn from spools. Attempts have also been made to place two or more spool creels, one in front of the other, in order to supply enough thread to reduce the number of sections. This has not been successful, due to the excessive strain put on the warp mill and because of the space required between these creels for access to the spools, which space caused the threads of one creel to cross the threads of the other creel at quite a large angle. The crossing of the threads makes the work of the operator more difficult in obtaining his lease, locating and tying in broken ends, etc., and also induces an undue amount of chafing, resulting in broken filaments that slub up on the guides and other parts of the device. By employing this invention, the

threads from the spools run substantially parallel to each other, which reduces the amount of chafing and overcomes the difficulties of the operator.

A further advantage of this invention is that the warp sheet from the creel may be run directly to a slashing device, thereby dispensing with the warp mill and its two re-winding operations. A still further advantage of this invention is that the device is compact, effecting an economy in floor space.

Creels, employed prior to this invention, that were adapted to use spooled thread, produced a large number of broken filaments, especially on low twist yarn. Broken filaments in threads of low twist are caught by the yarn guides and bunched up, resulting finally in a slub on the thread or a broken thread. Some of these broken filaments were caused by the thread coming from the spools on the lower part of the creel rubbing against the threads on the spools on the upper part of the creel. As the direction of travel of the unwound thread is in the opposite direction from the rotation of the spool against which it rubs, considerable abrasive action takes place, especially when the creel is run at a normal speed of about 100 yards per minute, making a relative speed between these two threads of about 200 yards per minute. The device forming a part of this invention is constructed in such a manner that the threads of the lower spools are guided away from contact with threads on the upper spools without increasing the space between the spools.

A further advantage of this invention is that the tension on each individual end is reduced, which results not only in less strain on the yarn, but in reduction of strain on the warp mill. This reduction of strain on the mill will reduce maintenance costs and the lower tension results in a saving in power costs.

This device also provides for rolling friction which produces a uniform tension on the thread when the thread is drawn from any part of the spool, regardless of the size or shape of the spool or package.

In accordance with our invention, we construct a creel for packaged threads such as bobbins or spools comprising two sets or banks of thread package holders which are arranged in such a manner that the sheets of threads coming from each bank leave the creel in relatively closely spaced, substantially parallel planes. Each bank of the creel is provided with a set of roller guides, one roller for each substantially vertical row

of packages, which guides are constructed for adjustment to an angle from the horizontal line of the warp sheet for the purpose of guiding the threads coming from one vertical row of packages away from contact with the adjacent vertical row of packages. This arrangement permits a large number of threads, running substantially parallel to each other to be drawn, without chafing, from the creel to a warp mill, slashing device or directly to a warp beam.

This invention may be employed in forming warps or warp-like packages from any suitable type of individual thread or package. It is particularly applicable, however, in forming warps from spooled threads formed of substantially continuous filaments such as the cap-spun spooled thread produced on synthetic yarn spinning or forming devices. For instance, the invention is particularly applicable to the formation of warps from threads containing substantially continuous filaments of silk, reconstituted or regenerated cellulose and/or organic derivatives of cellulose. The organic derivatives of cellulose may be, for example, the organic acid esters of cellulose or cellulose ethers. Examples of organic acid esters of cellulose are cellulose acetate, cellulose formate, cellulose propionate and cellulose butyrate, while examples of cellulose ethers are methyl cellulose, ethyl cellulose and benzyl cellulose.

The supply packages, to be used on the creel, may be of any suitable type, such as spools, bobbins, pins and like packages. The invention is, however, particularly applicable to the formation of warps from cap-spun bobbins or spools. The cap spun bobbins or spools may have the thread wound thereon as said thread is delivered from a synthetic yarn spinning device. These bobbins or spools may contain from less than $\frac{1}{16}$ of a pound to a pound or more of thread, which thread may have a twist of from less than one to four or more turns per inch. Threads having high degree of twist, say from four to seventy turns per inch may also be formed into warps by employing a device constructed in accordance with our invention.

Although the invention is of particular importance in the formation of warps from low denier threads, such as those containing continuous filaments of silk, reconstituted or regenerated cellulose, or organic derivatives of cellulose, the same may be employed in the formation of warps from higher denier threads such as those formed from cotton, wool, linen or other textile material. For instance, in employing threads of such a denier that formerly two sections were placed upon a warp mill to form a complete warp, by employing this invention the complete warp may be made in one section. Also, where the threads employed were of a low denier requiring six or more sections to be placed on a warp mill to form a complete warp, by employing this device the number of sections may be reduced 50% or even more.

In the drawing there is shown a device constructed in accordance with our invention. This device may comprise a main frame 1 in cross-section, resembling an inverted V. The legs 2 and 3, of which there may be any suitable number of pairs that form the inverted V, may be suitably attached to each other by a pivot rod or by suitable pivot pins 4. The pivot rod 4 may run the full length of the device and join all the legs in pairs or each pair of legs may be provided with an individual pin. The pivot rod 4 prefer-

ably passes through eyes 5 formed in the upper ends of the legs 2 and 3.

A plurality of pairs of legs 2 and 3 forming inverted V members may be suitably spaced and connected to each other by means of horizontal or cross pieces 3. Suitably attached to the cross pieces 3 on each side of the device are strip members 11. The strip members 11 may be provided with a plurality of pins 12 adapted to be inserted in the hub of a spool or bobbin to support the same. In place of pins 12 there may be provided any other suitable support for the particular type of supply packages employed. The pins 12 may be stationary or rotatable and may be formed of any suitable material such as wood, steel, vulcanized fiber, etc. The strips 11 are placed on the cross members 3 at a slight angle to the vertical and are so spaced that threads coming from the spools mounted on the bottom pins 12 may clear the spools mounted on the top pins 12 of the adjacent row.

On the main frame, for instance, on the legs 2 are suitable brackets 13 spaced at suitable intervals across the device, which brackets are connected to each other by an angle iron or other suitable member 14. Mounted upon the angle iron 14 above each substantially vertical row of spool supporting pins 12 is a bracket and bearing member 15 which may consist of a base 16 having two upright arms 17 and 18 projecting therefrom. The arms 17 and 18 are connected by a pin or axle adapted to support a roller 19. The bracket 15 is preferably attached to the cross member 14 by means of suitable screws 21. For the purpose of adjusting the angle that the roller 19 makes with a line passing through a row of pins 12, there may be provided set screws 20 threaded into the member 14 and bearing against the base 16 of the roller support. The roller member 19 is adapted to guide the threads coming from one row of spools to a comb 22. By means of the set screws 20 or other suitable device, such as shims, the roller 19 may be set at an angle to the horizontal, thus causing it to guide the threads in such a manner that the thread coming from the bottom spool of one row does not touch the yarn wound upon the top spool of an adjacent row. This greatly reduces the number of broken filaments in that it prevents a rubbing contact between the thread travelling up to the roller guide and the yarn on the rotating spools. Arms 24 may be provided at each end of the device suitably attached to the leg 3 by means of brackets 25, which arms have attached thereto brackets or upright members 26. The members 26 may be connected together by an angle iron or other suitable support 14, which support may have mounted thereon roller guides 19 in the same manner as described above. Also mounted on the arms 24 may be suitable frame members 29 also adapted to support a suitable comb 22 and thread detector 28. Adjustments of the combs may be made by means of adjustment screws 31 while adjustment of the frames 27 and 29 may be made by means of slots 30.

For the purpose of positioning the creel in front of a leasing device, a warp mill, a warp beam or slashing device, there are provided suitable wheels 32 mounted on suitable axles 33 and 34. For the purpose of adjusting the angle of the banks of spools such that the warp sheets will register with the device upon which the threads are being wound, and such that a balance between tension and jumping of spools may be maintained, there may be provided an adjust-

ing means operating on the lower ends of the legs 2 and 3. The adjusting mechanism may comprise a female slide member 38 pivotally connected to the leg 3 by a suitable retaining bolt 39 and a male slide member 41 pivotally connected to the leg 2 by a suitable retaining bolt 42. The free end of the slide 41 is formed having a slot 43 adapted to receive an ear 44 formed on the slide 38. An ear 45 may also be provided on the slide 41. The ear 44 may be provided with a bearing adapted to receive a thrust bearing 46 of a threaded rod 47. The ear 45 may be provided with a threaded opening adapted to receive the threaded end of the rod 47. By turning the rod 47 the legs 2 and 3 may be adjusted to a suitable angle.

In operation of the device filled spools or bobbins 36 are placed upon the two banks of supporting pins 12, thus forming two banks of spooled packages of thread. These banks are so arranged that the supply packages are run in substantially vertical rows spaced sufficiently far apart to allow the withdrawal of thread from one row of spools between that row of spools and the adjacent row of spools. The group of threads coming from one row of spools is led over the roller 19, threaded through the electrical thread detector 28 and comb 22 and thus on to a guide roller or through a leasing comb forming a part of any suitable winding device, for instance, warp beam, warp mill or slashing device. By arranging the two banks of supply packages in the form of an inverted V the distance between the guide rollers above one bank of the V and the guide rollers above the other bank of the V is relatively small. By having the distance between the two sets of guide rollers relatively small, the yarns coming from both sets of guide rollers to a comb or guide roller on the warp winding device travel in substantially parallel lines without crossing each other or without frequently engaging with each other. The two sheets of warp threads coming from the two sets of guide rollers move with an equal speed in the same direction, thereby preventing any possibility of one thread abrading another to break individual filaments in the threads.

The threads 37 may be drawn over the guide rollers 19 to any suitable type of warp-winding device. For instance, the threads may be drawn over the rollers 19 to a comb of a type normally employed in a leasing device when forming warps in a sectional manner upon a warp mill or the threads may be drawn to a heddle and then on to a warp mill or directly on to a warpbeam. The threads may also be drawn over the rollers 19 directly to a warp beam or first to a comb and then on to a warp beam. In place of the warp beam the threads may pass either directly into a slashing device of the type normally employed in the sizing of warps, or the threads may first pass through a comb or other guide and then into a slasher.

In place of strips 11 there may be employed a solid sheet of material having mounted thereon pins or pegs 12 suitably spaced and arranged to form supports for the rows of spools. The pins 12 may be formed of any suitable material, for instance, wood, metal or vulcanized fiber. The roller guides 19 may be made of metal, glass or vulcanized fiber and they may be mounted upon supporting axles or they may be otherwise suitably journaled into the upright members of the brackets 16. For the purpose of reducing friction, it is preferable to support the rollers 19

on ball-bearings or other anti-friction bearings. The combs 22 and the thread detectors 28 may be of any conventional design. The combs 22 may be in sections of suitable size to accommodate the threads from one row of spools or they may be in larger sections, each section being adjustable. Other modifications of the device from that shown in the drawings may be made without departing from the spirit of my invention. Provision may be made for grounding the device to prevent the storage of static electricity.

Our device forming a part of the invention employing roller guides in sections corresponding to the substantially vertical rows of spools, produces a warp having less broken and otherwise deflective ends and a warp in which each end has the same tension. The tension of yarn passing over stationary guides varies approximately in direct proportion with the arc of contact. Due to the short distance between the top row of bobbins and the guide the arc of contact between thread and guide varies from 70 to 140° as the yarn unwinds from the top to the bottom of the traverse. Also in employing threads of low twist which pass over the guides in the form of ribbons along with threads of high twist which pass over the guides in a cylindrical shape, the tension of the threads on the stationary guides may vary say from 60 grams in low twist yarns to 15 grams in high twist yarns. The present device reduces the tension on all yarns to practically nothing, thus permitting the marking of a warp with a lower and even amount of stretch on each yarn. There is also but a fraction of the strain on the mills when employing our device that would be placed on other devices winding the same number of ends.

The tensions obtained by employing this invention are lower and show less fluctuation than those obtained with any other type of bobbin creel. As the roller is turning at the same speed as the yarn travels, the arc of contact or the percentage of the circumference of the roller which is in contact with the yarn, has absolutely no bearing on the tension produced. Also by setting the individual rollers at a slight angle, it is possible to have the yarns from a given row of bobbins run close enough together so that the chafing between such yarns and the bobbins of the adjacent row is eliminated.

There is less tendency for fly or broken filaments to collect on the guides forming a part of the present invention than on other types of guides.

Having described our invention, what we desire to secure by Letters Patent is:

1. A warping creel for forming ribbons of threads from a plurality of thread supply packages, comprising a frame in the form of an inverted V, the legs of which frame are pivotally attached to one another, means attached to said legs for moving the legs relative to each other so as to enable the height at which the threads 65 are led from the creel to be varied, and means on each leg of the frame for supporting a bank of supply packages, the construction and arrangement being such that a ribbon of threads leaving the supply packages on one leg of said frame lies in a separate plane which is substantially parallel and in close proximity to the plane in which lies a ribbon of threads from the supply packages on the other leg of said frame.

2. A warping creel for forming ribbons of 75

threads from a plurality of thread supply packages, comprising a frame in the form of an inverted V, means on each leg of the frame for supporting a bank of supply packages, rollers on said legs, one for each ribbon of threads made up of threads from a vertical row of supply packages, for guiding the threads coming from each bank of supply packages, and means for adjusting said rollers angularly with respect to the horizontal, the construction and arrangement being such that a ribbon of threads from the supply packages on one leg of said frame lies in a separate plane which is substantially parallel and in close proximity to the plane in which lies a ribbon of threads from the supply packages on the other leg of said frame.

3. A warping creel for forming ribbons of threads from a plurality of thread supply packages, comprising a frame in the form of an inverted V, means on each leg of the frame for supporting a bank of supply packages, rollers on said legs, one for each ribbon of threads made up of threads from a vertical row of supply packages, for guiding the threads coming from each bank of supply packages, a mounting for each of said rollers, screw means for securing said mounting to one of said legs, and screw means at each end of said mounting for adjusting the angular position of said mounting and said roller

with reference to the horizontal, the construction and arrangement being such that a ribbon of threads from the supply packages on one leg of said frame lies in a separate plane which is substantially parallel and in close proximity to the plane in which lies a ribbon of threads from the supply packages on the other leg of said frame.

4. A warping creel for forming ribbons of threads from a plurality of thread supply packages, comprising a frame in the form of an inverted V, the legs of which frame are pivotally and adjustably attached to one another, means on each leg of the frame for supplying a bank of supply packages, rollers on said legs, one for each ribbon of threads made up of threads from a vertical row of supply packages, for guiding the threads coming from each bank of supply packages, and means for adjusting said rollers angularly with respect to the horizontal, the construction and arrangement being such that a ribbon of threads from the supply packages on one leg of said frame lies in a separate plane which is substantially parallel and in close proximity to the plane in which lies a ribbon of threads from the supply packages on the other leg of said frame.
